(57) **CLAIM**

The ornamental design for a car tail light cover as shown and described.

DESCRIPTION

FIG. 1 is a front, right and top perspective view of a car tail light cover, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1; and, FIG. 10 is an enlarged view of detail 10 in FIG. 2.

A second embodiment includes the mirror image of the car tail light cover shown in FIGS. 1-10.

The dashed broken lines depict portions of the car tail light cover that form no part of the claimed design.

The dot-dash broken lines in FIGS. 1, 2, 9 and 10 depict the boundaries of the enlargements and form no part of the claimed design.

1 Claim, 10 Drawing Sheets
